UNITED STATES PATENT OFFICE.

EARL LEE, OF CORONA, NEW YORK.

PORTABLE HOUSE.

SPECIFICATION forming part of Letters Patent No. 231,593, dated August 24, 1880.

Application filed May 7, 1880. (No model.)

To all whom it may concern:

Be it known that I, EARL LEE, a citizen of the United States, residing at Corona, in the county of Queens and State of New York, have invented certain new and useful Improvements in Portable Houses; and I hereby declare the following to be a full, clear, and exact description of the same, reference being had to the accompanying drawings, (in two sheets,) making a part of this specification.

This invention relates to improvements in houses for use in camping out in the woods and elsewhere; and its object is to construct the house in such a manner that it will be very light, and at the same time very strong and firmly united together, and may be easily transported and readily put together without the aid of nails or screws or similar appliances, and will be comparatively inexpensive.

The invention consists, first, in the general construction and arrangement of the parts, as hereinafter particularly described, whereby a complete building is obtained which can be put up very easily and quickly without the use of nails, screws, or similar appliances; secondly, in the construction of the braces and the mode of applying them by means of turn-buckles, so that the building shall be very light, and at the same time very strong and firmly connected in its several parts; thirdly, in the improved means for connecting the trussed floor-supporting beams to the posts, so that the same can be slipped into and out of position very readily and quickly; and, fourthly, in the novel combinations of parts whereby the several objects above mentioned are attained.

In the accompanying drawings, Figure 1 represents an isometrical perspective view of a portable house with my improvements, parts thereof being broken away to show more clearly its construction; Fig. 2, a sectional elevation of a portion of one of the corner posts and the sills, showing the mode of connecting the siding and posts and the posts and sills; Fig. 3, a plan of portions of the floor-beams, showing the mode of connecting the same to the posts; Fig. 4, a longitudinal vertical section of the building, taken through its center; Fig. 5, an end elevation of the

frame; and Fig. 6, a transverse section, showing the construction of the roof.

Similar letters of reference indicate the same parts in all the several figures, Figs. 1 and 4 being drawn on a scale of one-fourth of an inch to a foot and the remaining figures on a scale of three inches to a foot.

The said drawings represent a house ten and one-half feet wide by eighteen feet long, which I consider to be a convenient size for ordinary purposes; but it can be made larger or smaller, if desired.

A A' represent the sills, which are about two by three inches, and which support the posts B B'. The corner-posts B are two inches square and the intermediate posts B' are one and one-fourth by two inches and placed about eleven inches apart.

The sills are grooved, as shown in Fig. 2, to receive tongues *a* on the lower ends of the posts, and each of the posts is grooved lengthwise to receive the edges of the siding C. The siding, and also the roofing C', is made from three-eighths-inch board, and at the upper and lower ends of each piece are cleats *b* to prevent their warping.

D D are the eave-plates, and E the ridge, each of which is about two by three inches. The plates D D are grooved on the under side to receive tongues formed on the upper ends of the posts B', and the ridge E is grooved to receive the ends of the roofing-boards C'.

Cross-sections of the plates and ridge are shown in Fig. 6.

F represents the rafters, which are about one and one-fourth by two inches, and are grooved lengthwise to receive the edges of the roofing-boards C'.

G G' represent the floor-beams, which are about one inch by two and one-fourth inches. The said beams G, which support the lower floor, are supported by the sills, their ends being let into mortises in the same, and the beams G', which support the second floor, are connected with the posts B B' by means of a dovetailed metal casting, *d d'*, (shown in Figs. 3 and 6,) so that the said beams can be placed in and taken out of position by simply inserting the dovetailed portion *d* (which is secured on the end of the beam) into the socket *d'*

(which is secured to the post) when placing the beams in position, and withdrawing the same in taking the house apart.

The flooring I is of five-eighths-inch boards 5 laid down side by side, with their ends slipped into grooves i in the end sills on the lower floor and in beams J on the upper floor to keep them from rising. One or more additional transverse beams may be employed, so 10 that the flooring can be cut into shorter lengths, if desired.

By means of these constructions the parts are connected by tongue-and-groove connections, and no nails or screws are required in 15 putting the building together.

The floor-beams are trussed by means of wires m m', which are tightened over beams y y', running transversely across the centers of the beams and mortised at intervals to receive 20 the edges of the beams G', as shown in Fig. 4, so that the said beams y can be placed between the floor-beams and the wires m m', and then turned edge upward to tighten up the wires.

25 The ridge is trussed, as shown in Fig. 4, by means of the wire n, passed under the ends of the posts x x and tightened up by a turn-buckle, n'.

The building is braced by means of wires 30 tightened up by turn-buckles.

In Fig. 5 and partly in Fig. 2 is shown the mode of bracing the corner-posts and end sills, o o being wires attached to a ring, o', the upper ends of the said wires being connected 35 to rings or staples secured to the posts at their upper ends, and the lower ends of each of the said wires being passed through a ring, o², secured to the sill, and from thence to a ring, o³, secured to the post at the lower end of the 40 same, and tightened by turn-buckles q.

The corner-posts and side sills are braced, as shown in Fig. 4, by means of wires p, provided with turn-buckles p', so that by the 45 conjoint action of the wires o and p the posts are firmly braced to the sills, and the ridge is

braced by means of wires r, tightened up by turn-buckles r', said wires being secured, respectively, to the ridge and each of the eave-plates, and running at an angle from the perpendicular, as shown, so as to prevent any 50 end movement of the ridge.

The end rafters are braced as shown at u u in Figs. 1 and 5.

N represents a step-ladder, by which access is had to the second floor, and which is also 55 used when putting up the house. This ladder is composed of the two side pieces, s s, and the steps t, the said steps slipping into grooves provided in the side pieces, so that the ladder can be taken apart when desired. 60

What I claim as my invention is—

1. In a portable house, the combination of the sills A A', posts B B', eave-plates D, ridge E, and rafters F, each provided with grooves to receive the siding and roofing, respectively, 65 with the siding C and roofing-boards C', the several parts being constructed and arranged substantially as described, and the whole being braced by means of wires and turn-buckles, substantially as set forth, so as to dispense 70 with the use of screws and bolts.

2. In combination with the end sill, A', and posts B B, the wires o, ring o', rings or staples o² and o³, and turn-buckles q, as and for the purpose set forth. 75

3. In combination with the metal casting in two parts, d d', the former secured to the post B' and the latter secured upon the end of the beam G', the truss-wires m', beams y', and flooring I, as and for the purpose set forth. 80

4. The combination, in a portable house, with the corner-posts B, end sills and side sills, A A', ridge-plate E, and eave-plates D, of the bracing-wires o, p, and r, each provided with turn-buckles, as and for the purpose set forth. 85

EARL LEE.
